UNITED STATES PATENT OFFICE

119,769

DESIGN FOR A DISH TOWEL OR SIMILAR ARTICLE

Rodney Ruth, Chicago, Ill., assignor to Charles Schwartz & Company, Chicago, Ill., a corporation of Illinois

Application January 24, 1940, Serial No. 89,688

Term of patent 7 years

To all whom it may concern:

Be it known that I, Rodney Ruth, a citizen of the United States and resident of Chicago, in the county of Cook and State of Illinois, have invented a new, original, and ornamental Design for a Dish Towel or Similar Article, of which the following is a specification, reference being had to the accompanying drawing, forming a part thereof.

The figure is a plan view of approximately half of a dish towel or similar article, showing my new design, the balance thereof being conventionally plain.

I claim:

The ornamental design for a dish towel or similar article, substantially as shown, and described.

RODNEY RUTH.
